UNITED STATES PATENT OFFICE.

HENRY T. EDSON, OF ROCHESTER, NEW YORK.

CURTAIN OR SHADE GUIDE.

SPECIFICATION forming part of Letters Patent No. 451,665, dated May 5, 1891.

Application filed December 9, 1890. Serial No. 374,071. (No model.)

To all whom it may concern:

Be it known that I, HENRY T. EDSON, of Rochester, in the county of Monroe and State of New York, have invented certain new and useful Improvements in Curtain or Shade Guides; and I do hereby declare the following to be a full, clear, and exact description of the same, reference being had to the accompanying drawings, forming a part of this specification, and to the figures of reference marked thereon.

My present invention has for its object to provide a guide for window curtains or shades for preventing them from running crooked on their rollers, also to prevent their edges from excessive wear and friction, and to provide a device simple and cheap in construction and capable of being readily applied by an unskilled person; and to these ends it consists in a certain improved construction hereinafter described, and the novel features pointed out in the claims at the end of this specification.

In the drawings, Figure 1 is a view showing the application of my invention to a window-shade; Fig. 2, a view of the guide detached, and Figs. 3 and 4 views of modifications.

Similar figures of reference indicate similar parts.

As in Fig. 2, the main portion of the guide consists of a single piece of wire or similar material bent into the form shown, having two parallel arms 11, arranged close together and encircled by friction rollers or sleeves 22, preferably of celluloid or similar light material arranged to turn freely thereon, and the portion connecting said arms and extending at right angles to the opening between them is also encircled by a roller or sleeve 3, corresponding to those on the arms, against which the edge of the curtain or shade operates. In forming this frame the roller 3 is slipped on a piece of straight wire, the ends bent around, as shown, then the rollers 22 slipped on the arms 11, the shoulders 4 preventing their inward movement, and then the ends of said arms are upset, holding the rollers in place. This wire loop

arms in any suitable manner—as, for instance, by the wire arms 55, soldered or otherwise clamped to the loop, as in Fig. 2, said arms forming stops for limiting the longitudinal movement of the roller 3; or instead 55 a metal plate 6, as in Fig. 3, could be employed, having the ears 7 clamped around said portion and also constituting stops for confining said roller.

In the construction in Fig. 2 the wire arms 60 5 can be formed with loops 8 for the securing tacks or screws holding the device in position on the window-casing; or they may be left plain and straight, as in dotted lines, and, being more or less flexible, the user may 65 bend or shape them to hold the guide in any position desired and permit its application to shades running at an angle or horizontally—as, for instance, in photographers' or artists' studios, for which purpose these roller- 70 guides are especially advantageous.

While it is desirable to attach the flexible wire arms 5 to the central portion of the frame, as shown in Fig. 1, and to have them position the roller 3, this is not necessary, as 75 they could as well be applied to the ends of said loop, as in Fig. 4.

The plate 6 is cut from a single piece of material, and, as shown, the downwardly-extending part 9 is preferably perforated for 80 the passage of the securing screws or tacks.

The manner of using my invention will be clear from an inspection of Fig. 1, the guides being fastened to the window-casing and engaging the edges of the shade, as will be understood.

I claim as my invention—

1. A curtain or shade guide consisting, essentially, of the main frame made of a single piece of material with the two parallel arms, 90 the broad loop at the end, the roller mounted thereon, and the support for said frame, having the arms engaging the loop of the frame, substantially as described.

2. A curtain or shade guide having the 95 main frame composed of a single piece of material formed with the central straight part having the roller thereon, and the two arms extending at an angle therefrom, having rollers thereon and upset at the ends for retain- 100

ing said rollers in place, substantially as described.

3. A curtain or shade guide having the main frame composed of a single piece of material formed with the central straight portion and the two arms projecting therefrom, in combination with the support for said

frame consisting of the flexible wires attached thereto, substantially as described.

HENRY T. EDSON.
